FIRE-FIGHTING SYSTEM

William F. Conran, Brooklyn, N. Y.

Application January 4, 1933, Serial No. 650,117

16 Claims. (Cl. 169—2)

This invention relates to fire-fighting systems, and particularly to apparatus for extinguishing or preventing fire in inaccessible parts of a dock or other building, the term "dock" being used herein to indicate a wharf, pier or like structure.

There are many fires in which the flames spread by traveling along parts of the building which are not readily accessible to firemen and conventional fire-fighting equipment. Docks are a type of building or structure usually built over water and supported on piles, in which fires are particularly destructive, and these fires often spread along the under side of the dock floor. When a dock has side or curtain walls extending from the floor to the water, the under side of the floor is particularly inaccessible, but even without such walls, the short distance between the floor and the water level, and the presence of piling and cross-bracing, make it difficult to play streams of water over the under side of the floor to prevent the spread of fire or to combat flames already burning.

New and effective apparatus for fighting such fires on a dock or fires in other inaccessible buildings or parts of a building is disclosed in my Patent No. 2,006,709 dated July 2, 1935. The present invention relates to similar apparatus, but with different provision for moving the nozzle head along a course, and with other modifications of the structure.

An object of this invention is to provide a fire-fighting system for reaching fires at inaccessible places, more especially under the floors of docks and the like, and to provide novel and effective means for moving a nozzle carriage into positions for discharging water against the part of a dock or other structure.

Another object of the invention is to provide an improved nozzle carriage for movement along a supporting surface, and to provide improved operating means for moving the carriage. According to one feature of the invention, an endless cable moves the nozzle carriage and hose-supporting carriages which support a hose at one or more points behind the nozzle carriage.

The invention includes a nozzle head with wheels for movement along a track, and a plurality of nozzles radiating from the nozzle head to spray water to the front, rear and sides of the nozzle head over a substantial area. The reaction of the forwardly directed water jets causes a resultant force which tends to propel the nozzle head rearward along the track, and this force is opposed by the resultant force of the reaction of the rearwardly directed jets. If the reaction

of the jets is not to be used to assist in moving the nozzle head along the track, then the number of nozzles and their direction of discharge are chosen so that the resultant forces of the reactions forward and rearward substantially balance.

The invention also includes a combination of a dock or other building, a track, or plurality of spaced tracks, and a cable associated with each track for moving a nozzle carriage along the track. The invention can be constructed with each track terminating at a side of a dock, or adjacent an opening through a wall of a dock or other structure, so that a nozzle carriage can be placed on the track and be moved by the cable into the immediate vicinity of the fire by a fireman outside of the burning structure.

Other objects, features and advantages of the invention will appear or be pointed out as the specification proceeds.

In the accompanying drawings, forming a part hereof:

Fig. 1 is a sectional view of a wharf equipped with the fire-fighting apparatus of this invention;

Fig. 2 is a top plan view of the wharf shown in Fig. 1;

Fig. 3 is an enlarged side elevation showing the construction of the fire-fighting apparatus of Fig. 1;

Fig. 4 is a top plan view of the apparatus shown in Fig. 3;

Fig. 5 is an enlarged, sectional view on the line 5—5 of Fig. 3;

Fig. 6 is a detail sectional view taken on the line 6—6 of Fig. 5, but showing the cable lugs in elevation;

Fig. 7 is a view similar to Fig. 3 but showing a modified form of the invention; and

Fig. 8 is a section on the line 8—8 of Fig. 7.

A dock 11 is supported on piles 12 having conventional cross-braces 13. The dock has a floor 17 and sills 18 supported by the piles. Side or curtain walls 20 cover the upper portion of the piling, these side walls extending from the floor 17 downwardly to the water, though the level of the water with respect to the lower ends of the side walls 20 will vary through considerable range, depending on the tide or flood stage of the river. The invention is particularly useful for docks having these side walls because such walls make the under side of the dock very inaccessible. The invention is also useful, however, with docks having no curtain walls over the piling, and with other buildings or structures.

The fire-fighting apparatus can be operated from a boat, or by firemen working from ladders

45

50

55

55

22 which hook on the sills 18 and extend downwardly along the side walls 20. The side walls 20 have a plurality of openings 24 through which the firemen have access to the apparatus under 5 the wharf and can introduce nozzle heads.

The fire-fighting apparatus under the floor 17 is shown on an enlarged scale in Figs. 3-5. Hangers 38 are connected to angles 39 by bolts 40. The angles are fastened to the under side of 10 the dock. A plurality of equally spaced holes 42 in both the angles and hangers make it possible to change the distance between the hangers and the dock floor by bringing different holes of the angles and hangers into register and then inserting the bolts 40 through the holes chosen.

A flexible cable 44, which is shown as an endless cable, is supported by the hangers. The cable has lugs 46 secured to its top and sides at spaced points throughout its length. The side 20 lugs 46 slide along supporting guides 48 which extend along both sides of the cable. The guides 48 curve through an arc of 180° at each end, to reverse the direction of travel of the cable, but sheaves or other means can be used to reverse 25 the run of the cable in place of the curved guides.

The lower portions of opposing hangers 38 curve inwardly as shown in Fig. 5, and are clamped against the opposite ends of a spacing sleeve 52 by a bolt 54. A sheave 56 is rotatably 30 supported by an axle between each set of opposing hangers. The sheaves 56 are additional supports for the top run of the cable.

A nozzle head 62 is connected to one of the upstanding lugs 46 of the cable by a bolt 63. 35 If the nozzle head is of light weight, in proportion to the size of the cable and lugs, it can be supported entirely by the cable. Larger and heavier nozzle heads can be used, however, by providing side supports to hold the nozzle head upright, and the force required to move the nozzle head is greatly reduced by supporting all or most of the weight on rollers or wheels.

The nozzle head 62 has brackets or studs 65, shown in Fig. 5. A wheel 66 is rotatably connected to each stud 65. The wheels run on a track 67 which supports the weight of the nozzle head and keeps it in upright position. The rails of the track are supported by the hangers 38.

The nozzle head 62 is hollow and communicates 50 with a hose fitting 71, shown in Figs. 3 and 4. Water discharges from the nozzle head 62 through a plurality of nozzles 72 set at various angles.

Water is supplied to the nozzle head 62 through a hose 74 connected to the fitting 71 by a conventional screw-thread hose connection 75.

Fig. 5 shows two of the nozzles 72 in detail. Each nozzle includes a nipple 76 threaded into the nozzle head 62. A 45° elbow threads over the nipple 76 and a nozzle tip 77 is threaded into 60 the outer end of the elbow. The nozzle tip has a 22.5° bend and can be turned about its threads to change the direction of discharge of the water jet. Further adjustment of the direction of the water jet is made by turning the elbow on the threads of the nipple 76. These two adjustments combine to produce a very wide range of directions for the water jet. Simple non-adjustable nozzle tips threading directly into the nozzle head 62 can be used, if desired.

The nozzles are set at different angles for directing streams of water in a multitude of directions over a large area. The type of building, width of bays, and the spacing between tracks when parallel tracks are used, are important considerations in determining the setting of the noz-

zles. When used under a dock, as in Figs. 1 and 2, the nozzles are ordinarily set to discharge the water in a multitude of directions, upward, forward, rearward, and to both sides of the nozzle head. The reaction of the jets which incline forward causes a resultant force which urges the nozzle head rearward. The rearward inclined jets cause a resultant force in the opposite direction. In the nozzle head shown in the drawings the number of nozzles and their direction of 10 discharge is such that the forces of reaction in both directions substantially balance. The nozzle head can be made so that the reaction in one direction is greater than in the other and moves, or helps to move, the nozzle head in one direction along its course. When using a nozzle head which is moved in one direction by the reaction from the water jets, a single cable for moving the nozzle head in the other direction can be used in place of the double run, endless cable shown in 20 the drawings. I prefer the endless cable because it can not get out of place and can be used with any kind of nozzle.

Blocks 78 prevent the wheels 66 from running beyond the end of the track. The blocks 78 are 25 connected with the track by hinges 79, so that they can be swung out of the path of the wheels when the nozzle head is to be placed on or taken off the track. The block 78 at the left-hand end of the track in Fig. 3 is shown hinged down into 30 a position where it will not obstruct the wheels 66.

The hose 74 is supported at spaced points behind the nozzle carriage by hose-supporting carriages 85, each of which has a quickly detachable 35 hose clamp 86. Each hose-supporting carriage has a cross-bar 88 with wheels 89 for running on the track 67, and each of these carriages is fastened to a lug 46 of the cable by a bolt 90.

The connections between the hose-supporting 40 carriages and the lugs 46 have two functions; they cause the carriages to move with the cable, and support the carriages when their wheels are not on the track. Fig. 3 shows three hose-supporting carriages in inverted position and supported by the lower run of the cable.

When the nozzle head 62 moves to the right in Fig. 3, the lower run of the cable moves to the left and brings the lower hose-supporting carriages successively into position for clamping to the hose and placing on the rails 67. As the nozzle head 62 moves toward the left in Fig. 3, and each successive hose carriage reaches the end of the rails 67, it is unclamped from the hose and allowed to travel around the curved ends of the guides and along the lower run of the cable.

The cable is manually operated to move the nozzle head forward by grasping and pulling the cable, or one of the outwardly extending lugs 46 directly by hand, or by a tool which grips the cable, or connects with the lugs.

Fig. 2 shows a plurality of parallel tracks with nozzle heads at different positions on the tracks. The dotted lines radiating from each nozzle head 65 indicate the extent of the water streams and illustrate the manner in which the nozzles operating along the parallel tracks reach every part of the surface.

Figs. 7 and 8 illustrate a modified form of the 70 invention in which the wheels of the nozzle head and hose-supporting carriages run on an I-beam supported directly from the dock. The guides are supported by hangers 98, but fewer hangers are necessary, or they may be of lighter construc- 75

tion, since they do not carry the weight of the track, hose and nozzle head.

The nozzle head 100 of Figs. 7 and 8 comprises a body portion 102 with upwardly extending brackets 104, to which wheels 106 are connected.

The body portion 102 is hollow, and is connected to the hose 74 by a conventional screw coupling 75.

Fig. 7 shows a hose-supporting carriage 110 with wheels 112. These wheels and the wheels 106 of the nozzle head travel along a track 115 which is shown as an I-beam in Figs. 7 and 8. The hose-supporting carriage 110 clamps to the hose and moves with the hose, but is not connected to the cable.

The cable 44 is operatively connected with the nozzle head 100 by means of a bracket at the bottom of the nozzle head. This bracket is fastened to a lug of the cable by a bolt 118, or the bracket can be used as an abutment with which a lug of the cable contacts to push the nozzle head along the track.

The nozzle head 100 and hose-supporting carriage 110 are similar to those shown in my patent No. 2,006,709.

The operation of the system shown in Figs. 1-6 is as follows:

The firemen approach the dock from the windward side, and operating from a boat or ladders 30, 22 introduce the nozzle head 62 through one of the openings 24 adjacent the end of a track which runs close to the fire. The hose 74 is connected to the nozzle head and supplied with water from a fire-boat or water source on shore.

An upstanding lug 46 of the cable is fastened to the bracket at the bottom of the nozzle head, and a fireman operates the cable to move the nozzle carriage away from him along the track. The fireman can reach between the cable guides and 40 grip the cable directly, or he may pull it by seizing one of the upstanding lugs 46. The cable can be conveniently operated by using a tool to grip the cable or hook on the lugs of the cable.

When the nozzle head has traveled a short distance, a hose-supporting carriage 85 is placed on the track and clamped to the hose. As the nozzle head travels further, additional hose-supporting carriages are placed on the track and clamped to the hose. The spacing of these hose-supporting carriages is the same as the spacing of the lugs along the cable so that each hose-supporting carriage can be connected to one of the upstanding lugs 46.

The nozzle head can be stopped at any desirable location along the track, but in many cases it is most effective if moved back and forth along the track. When using the water to prevent the spread of fire, the nozzle head is moved back and forth to keep the surfaces wet along the entire length of the track.

A fireman can move the nozzle head toward him by pulling the hose. As each hose-supporting carriage returns to the end of the track it is unclamped from the hose but remains connected to the lug 46 of the cable. As the nozzle head and top run of the cable continue to move toward the fireman, the hose-supporting carriage which has been unclamped from the hose is carried beyond the end of the track and along the lower run of the cable.

When the cable is again operated to move the nozzle head forward, away from the fireman, the hose-supporting carriages connected to the lower run of the cable are successively brought around

by the cable into position to be placed on the track and clamped to the hose.

The invention has been described for use with a dock, and it is particularly useful with such structures because of the difficulty in reaching the under side of a dock with fire-fighting streams. However, the invention can also be applied to other buildings, and if one or both ends of the track are located at a door, window, or other opening, the carriages can be placed on the track 10 by a fireman outside the wall.

The preferred embodiment and one modified form of this invention have been described, but other modifications can be made, and various features of the invention can be used alone or in combination with other features without departing from the invention as defined in the claims.

I claim:

1. In a dock or like structure; a track supported by the dock beneath the dock floor in position to support a nozzle head for movement along the track; and an endless cable extending along the track for connection with the nozzle head to propel said nozzle head along the track, portions of said cable extending into positions 25 adjacent opposite sides of said dock for manual operation of the cable by a fireman at either side of the dock.

2. In a structure, fire protection apparatus including a track extending within the structure 30 from a wall thereof, said wall having an opening at the end of the track; an endless cable; means supporting the endless cable with at least one run of the cable extending along the track for operative connection with a nozzle head to move 35 the nozzle head along the track, a portion of the cable extending close to the opening for operation by a fireman at the wall opening.

3. In a structure, a fire protection system including a track within the structure; a nozzle head movable along the track; and a cable for propelling the nozzle head in at least one direction along the track; the structure having an opening through one of its walls with the opening located so that the cable can be operated to 40 propel the nozzle head by a fireman outside of said wall.

4. A fire-fighting device comprising a hollow nozzle head; axles extending from the sides of the nozzle head; wheels having a radius less than the distance between the axle and the lower end of the nozzle head, and carried on the axles for supporting the nozzle head for movement along a track located above the lower end of the nozzle head; and a plurality of nozzles radiating from 55 the nozzle head and directed to discharge fire-fighting jets of water upward, lengthwise, and breadthwise.

5. Fire-fighting apparatus comprising a nozzle head; wheels supporting the nozzle head for movement along a track; a plurality of nozzles radiating from the nozzle head and directed in different directions to discharge jets of water to both sides, forwardly and rearwardly of the carriage, the amount of water and direction of discharge 65 from the forwardly directed jets being such that the reaction of these jets produces a resultant force in the direction of the track which substantially balances a similar resultant force of the rearwardly directed jets.

6. Fire-fighting apparatus comprising a nozzle head; wheels supporting the nozzle head; a track on which the wheels run; a hose connection for supplying water to the nozzle head; an endless cable extending along the track for propelling 75

the nozzle head in one or both directions; means for operatively connecting the cable and nozzle head; and spaced supporting means for the cable.

7. Fire-fighting apparatus comprising a track; 5 an endless cable; means supporting the endless cable with at least one run of the cable substantially parallel to the track; a nozzle head, wheels running on the track and supporting the nozzle head for movement along the track; and connecting means between the cable and nozzle head for causing the nozzle head to travel with the cable.

8. Fire-fighting equipment including a wheeled nozzle head for movement along a supporting 15 surface; an endless cable for connection with the nozzle head to propel said nozzle head in at least one direction along the supporting surface; means for operatively connecting the cable and nozzle head; and cable guide means supporting the 20 endless cable at a plurality of points spaced along said supporting surface.

9. Fire-fighting equipment including a wheeled nozzle head for movement on and along a supporting surface; a cable extending along the 25 supporting surface for connection with the nozzle head for moving said nozzle head in at least one direction along the supporting surface; means for operatively connecting the cable and nozzle head; lugs connected to the cable at spaced points; 30 and cable guide means on which said lugs are slidably supported.

10. Fire-fighting apparatus including a track; a wheeled nozzle head mounted for movement along the track; a hose arranged for supplying 35 water to the nozzle head; hose-supporting carriages for connection with the hose at spaced points, wheels on said carriages mounted for running on the track; an endless cable; cable guide and supporting means adjacent the end of 40 the track for reversing the run of the cable; means connecting the nozzle head with the cable so that movement of the cable propels the nozzle head; and means connecting the hose-supporting carriages to the cable to propel said carriages 45 along the track when they are supporting the hose, and to support the carriages when they have moved beyond the end of the track and have moved away from the hose and around the cable supporting means which reverses the run of the 50 cable.

11. In a structure, a fire-protection system including a plurality of spaced tracks, each of which terminates at a wall opening through which a wheeled nozzle head can be placed on or taken off the track in position; and a cable ex-

tending along each track for connection to the nozzle head to propel said nozzle head along the track.

12. In a dock or like structure; a plurality of substantially parallel, spaced tracks extending across the dock below the floor for supporting nozzle heads with their wheels running on the tracks; an endless cable for each track; and means supporting each of the endless cables with at least one run of each cable extending along its 10 associated track for connection to a nozzle head to propel the nozzle head along the track.

13. In a structure to be protected from fire, a fire-fighting system including an endless cable, means supporting the cable for longitudinal 15 movement from one side to another of said structure through an inaccessible portion of the structure, said cable being accessible from either of said sides and means for connecting a fire-fighting nozzle head to the cable for movement as a 20 unit with the cable to carry water to a fire in said inaccessible portion of the structure.

14. Fire-fighting equipment including an endless cable extending through an inaccessible portion of a structure to be protected from fire and 25 accessible from two sides of the structure; cable supporting means connected with the structure for supporting a cable for longitudinal movement from one side to another of said structure, said cable being accessible from either of said sides; a 30 fire-fighting nozzle head transported by the cable along the course of said cable; and means for connecting the nozzle head to the cable.

15. Fire-fighting apparatus including a hollow body, upwardly-extending brackets connected 35 with the body; wheels on the brackets for supporting the body for movement along a track situated above said body; and a multiplicity of nozzles radiating from the hollow body and of such size and so directed that they deliver fire- 40 fighting jets of water upward, lengthwise, and breadthwise against an overhead surface.

16. Fire-fighting apparatus comprising a substantially rigid track, a nozzle head of such a nature that it can be readily placed on or removed from the track, means for connecting a hose to the nozzle head for supplying water to said nozzle head, a cable with at least one run extending along the track for propelling the nozzle head along the track, and detachable connecting means for quickly fastening the carriage to the cable when the carriage is placed on the end of the track by a fireman in the event of fire at some region along the length of the track.

WILLIAM F. CONRAN. 55
